UNITED STATES PATENT OFFICE.

FOREST S. ESKEW, CHRISTOPHER C. BRAGG, AND CHARLES E. ESKEW, OF HUNTINGTON, WEST VIRGINIA.

WINDOW SHADE AND CURTAIN HOLDER.

1,404,104.

Specification of Letters Patent. Patented Jan. 17, 1922.

Application filed November 5, 1920. Serial No. 421,947.

To all whom it may concern:

Be it known that we, FOREST S. ESKEW, CHRISTOPHER C. BRAGG, and CHARLES E. ESKEW, citizens of the United States, residing at Huntington, in the county of Cabell and State of West Virginia, have invented certain new and useful Improvements in Window Shades and Curtain Holders, of which the following is a specification.

10 This invention relates to devices for supporting window shades and curtains and has for its object the provision of a simple, inexpensive and efficient device which may be readily applied to windows of any width 15 and which, when applied, will firmly support the window shade and the curtains.

Secondary objects of the invention are to provide easily adjusted means for adapting the device to support wide or narrow shades 20 without restricting the user to curtains of a set width; to provide a device in which a broken or damaged part may be easily removed and a new part substituted therefor, and to provide a construction which will 25 permit the parts to be assembled in very compact form and will provide the necessary strength without excessive weight and, therefore, without causing breaking strain upon the window frame. A further object 30 of the invention is to provide a device which may be readily secured in position upon a window frame without marring any of the parts and without the use of nails or similar fastenings.

35 The invention is illustrated in the accompanying drawings, in which—

Figure 1 is a perspective view of one form of the combined window shade and curtain holder;

40 Fig. 2 is a plan view of the same showing a window frame in section and showing one application of the invention to the frame;

Fig. 3 is a similar view showing another method of applying the device to the window frame;

45 Fig. 4 is an enlarged longitudinal section with parts broken away;

Fig. 5 is an enlarged perspective view particularly showing the adjusting lever by 50 which the members of the main supporting bar are adjusted and set;

Fig. 6 is an enlarged end view;

Fig. 7 is a detail rear view of one end of the device;

55 Fig. 8 is a detail side elevation showing

another mounting for the principal locking lever;

Fig. 9 is a plan view of the structure shown in Fig. 8;

Fig. 10 is a longitudinal section showing 60 another form of the securing members;

Fig. 11 is an end view of the arrangement shown in Fig. 10;

Fig. 12 is a front elevation of the securing device shown in Figs. 10 and 11; 65

Fig. 13 is a perspective view of another form of the shade-supporting bracket;

Fig. 14 is a perspective view of another form of securing device;

Fig. 15 is a section on line 15—15 of 70 Fig. 14.

In carrying out our invention, we employ a base or main supporting bar consisting of telescoping members 1 and 2 of sheet metal provided along their side edges with overhanging flanges 3, the flanges on the member 1 fitting slidably in the grooves presented by the flanges on the member 2. The member 1 of this base bar is constructed with a series of openings 4 therethrough upon its medial 75 longitudinal line and the member 2 carries a locking dog which is adapted to engage any one of said openings and thereby lock the members in a set relative position adjusting the bar to the width of the window frame 80 or of the shade which is to be supported. Further adjustments are permissible as will hereinafter appear. As shown most clearly in Figs. 1 and 5, the member 2 of the telescopic main supporting bar is provided near 85 one end with a cruciform opening 5, the longitudinal branches of which are disposed upon the medial longitudinal line of the member whereby they will register with the openings 4 in the member 1, as clearly shown. The vertically disposed branches of the 90 opening are formed by striking from the bar tongues 6 which are bent forwardly, as shown, and form fulcrum brackets or lugs 95 for the locking lever 7. The said lever is constructed with a longitudinal slot 8 in its pivoted or fulcrumed end and at said end the branches of the lever are turned laterally for the locking lever 7. The said lever is 100 constructed with a longitudinal slot 8 in its pivoted or fulcrumed end and at said end the branches of the lever are turned laterally so as to constitute fulcrum pins or trunnions 9 which are rotatably engaged in openings 105 provided therefor in the tongues 6, as clearly shown. Within the recess or slot 8 and eccentric to the fulcrum pins or trunnions 9, we pivotally attach, as shown at 10, a pawl or dog 11 which is provided at its free end 110

with oppositely extending lugs or teeth 12 either of which is adapted to engage one of the openings 4 in the member 1, as will be readily understood. As indicated by the full 5 and dotted lines in Fig. 5, the dog may be swung about its pivot 10 so as to pass through the slot 8 and, consequently, either one or the other of the teeth 12 will be brought into engagement with one of the 10 openings 4 whereupon the rocking of the lever will effect relative longitudinal movement of the members 1 and 2, the direction of movement being determined by the position of the dog accordingly as the dog is 15 disposed at one or the other side of the lever. We thus very readily and in a simple manner adjust the members 1 and 2 of the main supporting bar to the width of the window frame and adapt the device without 20 any substantial change in construction to be used upon any window frame. At opposite sides of the cruciform opening 5, resilient tongues 13 may be struck up from the web of the member 2 and the free end of the lever 7 may be engaged under one or the other of these tongues after the device has been set so that accidental movement of the lever will be prevented and collapsing of the supporting bar thereby avoided. These tongues 25 may, however, be omitted as the lever is self-locking.

To secure the device upon a window frame, we provide, at each end of the main supporting bar, securing hooks 14 which are carried 30 by a base plate 15 and may be readily adjusted longitudinally of the main supporting bar. The members 1 and 2 of the main supporting bar as well as the base plate 15 may be conveniently formed from sheet metal, the 35 flanges 3 being produced by rolling or stamping the blank in an obvious manner. The base plate 15 has its side portions rolled or folded so as to be doubled over upon the main portion of the plate, as shown at 16, and the free edges of the plate are then turned outwardly to produce overlying flanges 17 which may be pressed about the shanks of the securing hooks 14 so as to effectually bind and secure the same. In the 40 form of the invention, shown in Figs. 1 to 7, the hooks 14 have their shanks 18 disposed parallel within the overlying flanges 17 and projected through and beyond the inner ends of said flanges, being brought together at the 45 inner end of the base plate 15 to provide a loop 19, as shown most clearly in Fig. 7, and a locking dog 20 is fulcrumed upon the shoulder or end portion of the loop or bail 19 produced by the inner ends of the shanks, 50 as shown in Figs. 4 and 7 and as will be readily understood. This locking lever or dog is provided with a tooth 21 disposed at a right angle to its main portion and adapted to enter one of the openings 4 in the base 55 member 1 so that when the locking dog is

turned home against the base plate 15 relative longitudinal movement of the members 1 and 15 will be prevented. It will thus be seen that we provide very simple and efficient means whereby the securing hooks 14 may be 60 adjusted longitudinally of the main supporting bar and the device adapted for application to window frames of any width. It will also be readily understood that by releasing the dog 20 the base plate 15 with the 65 hooks carried thereby may be slid out through the ends of the grooves defined by the flanges 3 and thereby separated from the main supporting bar. The securing device may then be reversed end for end and again 70 engaged in said flanges so that the hooks will be disposed at the inner end of the device instead of the outer end as before and thereby adapted to engage the inner edges of a window frame instead of the outer edges. 75 In Fig. 2, we have shown the device adjusted to be secured upon a window frame 22 of considerable width, whereas in Fig. 3 we have shown it adjusted to be applied to a window frame 23 which is narrower than 80 frames generally used. The manipulation of the device to adjust the hooks to the width of the frame and to secure them in set position relative to the main bar is exactly the same whether the hooks be disposed as 85 shown in Fig. 2 or as shown in Fig. 3. After the hooks have been adjusted to the width of the window frame, the setting lever 7 is manipulated to effect the necessary longitudinal movement of the telescopic main bar 100 so as to force the beaks of the hooks into the window frame, as will be readily understood. It will also be understood, of course, that one of the base plates 15 with the hooks carried thereby is mounted on the member 1 105 of the main bar, while the other plate is mounted upon the member 2. It will also be readily noted that the outer member 2 of the main bar is provided with a longitudinal series of openings 24 corresponding in all respects to the openings 4 in the inner member 1, but the openings 24 do not extend the full length of the said outer member 2, terminating short of the cruciform opening in which the setting lever 7 is mounted. The relative 110 lengths of the members 1 and 2 will be sufficient to accommodate the normal range of standard widths of window frames, but if it should be desired to apply the device to an excessively wide window, a longer member 120 1 may be provided, the length of the member 2 remaining fixed.

In addition to the parts previously described, we provide brackets for supporting the window shade and the curtains and these 125 brackets are also longitudinally adjustable upon the respective members 1 and 2 of the main bar. The brackets may be conveniently struck up out of sheet metal and each comprises an outwardly projecting arm 25 having 130

openings 26 therein to receive the trunnions of the usual window shade roller in an obvious manner. The arm 25 projects from a base plate or slide 27 provided at its side edges with overhanging flanges 28 adapted to slidably fit upon the upper and lower edges of the respective members of the main supporting bar. A resilient tongue 29 is struck up from the base plate 27 and upon the said tongue we provide a teat or protuberance 30 adapted to enter one of the openings 4 or 24, as the case may be, and thereby hold the bracket in the position in which it may be set. The free end of the tongue 29 projects outwardly somewhat from the base plate 27, as shown at 31; so that it may be easily manipulated when necessary. By adjusting the brackets longitudinally of the main supporting bar, the device is adapted to support a window shade roller of any length and this adjustment is obviously independent of the adjustment of the securing devices 14 and of the telescopic adjustment of the main bar so that the apparatus may be easily set to accommodate any given set of circumstances. In Fig. 3, we have shown a portion of the shade roller at 32, and at 33 we have shown a curtain pole or rod which is supported by having its ends fitted in notches or recesses 34 formed in the upper edges of the arms 25. At the extremities of the arms 25, we provide the upstanding pins 35 which are adapted to enter openings provided in a well-known form of curtain rod which is frequently used so that our device may be utilized to support curtain poles or rods of either type.

While the construction heretofore described answers all the demands of economy and efficiency, it may be desirable sometimes to employ the mounting shown in Figs. 8 and 9 for the locking lever. In this arrangement, bearing lugs 40 are formed upon the outer member 41 of the telescoping main bar and in the said lugs are inverted T-shaped openings or slots 42. The locking and setting lever 43 is provided with an enlarged body 44 at its fulcrum or pivotal end which is preferably circular in cross section. This body carries a radial tooth or locking lug 45 adapted to engage one of the openings in the inner telescoping member of the main bar and at its ends is provided with trunnions or pivot pins 46 receivable in the slots 42. When the lever is being swung in order to effect the desired adjustment of the main bar, the pins or trunnions 46 will each engage one end of the head or horizontal branch of a slot 42 and will thereby exert a longitudinal shifting force through the tooth 45 upon the inner member of the telescoping bar so that the desired adjustment will be effected. After the bar has been adjusted as desired a slight vertical movement of the body 44 will bring the

pins or trunnions 46 into engagement with the vertical branches of the T-shaped slots 42 and will thereby prevent relative longitudinal movement of the members of the bar so that it will be maintained in its set position. 70

In Figs. 10, 11 and 12, we have illustrated a form of securing device different from that previously described. In the form shown in Figs. 10, 11 and 12, we employ a sheet metal blank, substantially as shown in Fig. 12, having an elongated main portion or body 50 provided at one end and intermediate its ends with lateral tongues or wings 51 and 52, the wings 51 being retained in the plane of the main portion 50 and provided with a teat or protuberance 53 which, when the device is in use, is adapted to engage one of the openings 4 or 24 as the case may be. The wings 52 are bent laterally with respect to the side edges of the main portion 50 so as to be offset therefrom, as shown at 54, and they are then turned upwardly and downwardly to lie substantially parallel with the main portion and the wings 51, as shown most clearly in Fig. 11. Beyond the wings 52, the main body 50 is bent laterally, as shown at 55, and the end of the said portion 55 is then bent rearwardly and tapered, as shown at 56, to provide a hook or tooth adapted to penetrate the wood of the window frame and secure the device in place. It will be readily seen that this construction is very cheap inasmuch as the entire device may be produced in a metal stamping machine at a single operation and the cost of production thereby minimized. 95

By referring to Fig. 6 particularly it will be noted that the flanges 3 of the inner member 1 of the telescoping bar provide grooves receiving the edges of the base plate 15, and the flanges 28 of the window shade brackets engage over or around the said flanges 3. 105

In Fig. 13 we illustrate another form of bracket for carrying the curtains and shade-roller. In this form of bracket, the base plate 60 is provided at its upper and lower edges with overhanging flanges 61 to slidably engage the main supporting bar and at the inner end of the base plate a shade-roller carrying arm 62 projects forwardly. A resilient tongue 63 extends from the inner end of the base plate and is provided with a protuberance to engage one of the openings 110 in the main bar to hold the bracket in a set position. Lugs or supporting tongues 64 are struck out from the base plate to be engaged by and support a well-known form of flat curtain bar, said lugs having retaining teeth 65 at their upper ends. Alternating with the lugs 64, clasps 66 project from the base plate to secure a popular form of round curtain rod. 125

In Figs. 14 and 15 we show another form 130

of securing hook in which the base plate 67 is provided with a slightly offset extension 68 at one end. The hooks 69 are formed at one end of a plate 70 which is provided at 5 its opposite end with reflex spurs 71 to pass through slots 72 in the offset portion of the extension 68, a handle or tongue 73 projecting from the plate between the spurs to facilitate the assembling of the parts. Between the hooks 69 a tooth 74 projects rearwardly to engage one of the openings in the main bar and hold the hooks in a set position.

In all forms of the invention the device is 15 very simple in construction, compact in arrangement and easily adjusted to support window shades of any desired width or to conform to window frames of any desired width.

Having thus described the invention, what is claimed as new is:

1. In a device for the purpose set forth, the combination of a base bar consisting of inner and outer members fitted telescopically 25 together, the inner member having a longitudinal series of perforations therethrough and the outer member having a longitudinal slot exposing some of the perforations in the inner member, a lever fulcrumed upon the 30 outer member at the sides of the opening therein and having an open-ended slot at its pivotal end, and a dog pivoted within said slot eccentric to the fulcrum of the lever and provided at its free end on each 35 side with a lateral tooth to engage a perforation in the inner member of the base bar,

the dog being reversible through the opened slot in the lever.

2. The combination of a base bar having a longitudinal series of perforations, a bracket 40 having its upper and lower edges slidably engaging the upper and lower edges of the base bar, and a longitudinally extending resilient tongue struck up from the bracket having its free end projecting forwardly 45 from the bracket and provided on its rear side intermediate its ends with a protuberance to engage a perforation in the base bar.

3. The combination of a base bar having a longitudinal series of perforations, a plate 50 having sliding engagement with the base bar, a securing hook projecting from one end of the plate, and a swinging tooth carried at the opposite end of the plate to engage a perforation in the base bar.

4. The combination of a base bar having a longitudinal series of perforations, a plate 55 slidably mounted in the base bar, a securing hook projecting from said plate and having its shank fixed to the plate, a shoulder at 60 the inner end of the shank, a lever fulcrumed on said shoulder, and a tooth carried by and extending laterally from the lever at the fulcrum thereof to engage a perforation in the base bar whereby to effect longitudinal 65 adjustment of the plate.

In testimony whereof we affix our signatures.
